LOCK

Charles Ledin, Stamford, Conn., assignor to The
Yale & Towne Manufacturing Company, Stamford,
Conn., a corporation of Connecticut

Application October 30, 1945, Serial No. 625,608

10 Claims. (Cl. 292—33)

1
This invention relates to a lock, and more particularly, a lock of the type adapted for push and pull action, with suitable control mechanism for preventing release of the lock through said push and pull action. Even more particularly, the invention relates to a type of lock especially adapted for application to the doors of bathrooms.

As a feature of the invention, the lock utilizes a latchbolt that is adapted to be cammed rearwardly upon swinging movement of the lock and latchbolt with the door relatively to a strike, the swinging movement being effected by push and pull action. This push and pull action is preferably obtained by the utilization of knobs applied relatively to the inside and outside of the lock.

As a further feature of the invention, the lock provides a deadbolt that is cooperable with the strike for preventing movement of the lock relatively to the strike by push and pull action, the deadbolt being movable into locking position by one of the knobs that is used to impart push and pull action. As still a further feature of the invention, the deadbolt is adapted for retraction by the latchbolt in the event the deadbolt is projected when the door is open and the door is then shut.

The nature of my invention will be more clearly apparent upon a study of the drawings and the full description thereof in the specification that follows. It is important that my invention be not limited to the mechanical means that I have devised for contributing the features of the invention, as those skilled in the art will readily understand how the invention may be embodied in other mechanical forms.

Referring now to the drawings, Fig. 1 is a horizontal section taken through my lock and the strike with which it coacts, along the lines 1—1 of Fig. 2. Fig. 2 is a section taken along lines 2—2 of Fig. 1. Fig. 3 is a section taken along lines 3—3 of Fig. 2, the relation of the projected deadbolt to the latchbolt and the strike when the door is closing, being illustrated in dotted lines. Fig. 4 is a section along lines 4—4 of Fig. 2. Fig. 5 is a vertical view of the strike of my invention.

Referring now more particularly to the drawings, reference numeral 10 indicates a door to which my lock may be applied, while reference numeral 11 indicates a door jamb on which is mounted the strike 12 best shown in Fig. 5. The door 10 is formed with an opening 13 within which is mounted the casing 14 of my lock. This casing is preferably formed of two parts 15 and 16, as best shown in Fig. 4, held together by suitable means to form the casing.

2
Slidably mounted within the casing 14 is a latchbolt 17 whose head 18 is bored for a pin 19 on which is mounted a roller 20. A spring 21 lies at one end within a bore 22 of the latchbolt 17, and presses at its other end against a lug 23 extending from the casing 14. Naturally, the spring 21 acts to project the latchbolt 17 relatively to the casing 14 and toward the strike 12.

The strike 12 is formed with cam lugs 24 between which lies the bolt head 18 with its roller 20 bearing against the said cam lugs 24. It is obvious that a push or pull on the door 10 will swing casing 14 and effect a retraction of the latchbolt 17 due to the camming effect of the cam lugs 24 against the roller 20. Such push or pull action is contributed by an outside knob 25 and an inside knob 26. The outside knob is held in place by a rose 27 secured to the door by screws 28. The inside knob 26 is held in position by a rose 29 secured in place by screws 30. There is secured to the inside knob 26, through screw 31, a spindle 32 that extends into the lock casing 14 as is best apparent from Figs. 1 and 2.

Mounted within the lock casing 14 is a deadbolt 33 formed with rack portions 34. These rack portions are adapted for coaction with the teeth of a pinion 35 that is formed for traversal of the spindle 32. It is obvious, of course, that the spindle 32 will rotate the pinion 35 so that its teeth will mesh with the teeth of racks 34 to project or retract the deadbolt 33.

The deadbolt 33 is mounted with its head 36 lying juxtaposed to the head 18 of the latchbolt 17. Upon rotation of the spindle 32, the head 36 of the deadbolt 33 may be thrown into the opening 37 of the strike 12 so as to lock the casing 14 and the door 10 against movement through push and pull action of the knobs 25, 26. It will be noted that such locking takes place upon rotation of one of the knobs that is adapted to contribute push and pull action. Thus, any one contacting the knob 26 may open the door by pulling on the said knob, or he may rotate the knob to move the deadbolt 33 with its head 36 into the strike opening 37. To open the door thereafter, the operator will rotate the knob 26 to retract the deadbolt 33 and will then apply pull action.

It sometimes happens that the deadbolt 33 is projected relatively to the casing to its position 50 of Fig. 3, or its dotted line position of Fig. 2, when the door is open. In that event, the slamming shut of the door might lead to damage to the door and the lock mechanism unless means are provided for retracting the deadbolt. For contributing such action, I round one portion of the

deadbolt as designated by reference numeral 40 in Figs. 3 and 4. This rounding of the deadbolt makes it possible for the surface of the ring 20 to extend beyond the deadbolt head 36 as best seen in the dotted line position of Fig. 3. Because of this relationship of the parts, even with the deadbolt 33 projected, it will be the ring 20 of the latchbolt head 17 that will first contact the lip 39 of the strike when the door is slammed shut at the time the deadbolt is projected.

It will be appreciated also that when the deadbolt is projected, its shoulder 33a lies against the surface 18a of the head 18 of the latchbolt 17 as seen in dotted lines in Fig. 2. Therefore, the consequent retraction of the latchbolt through contact of ring 20 with the lip 39 of the strike, will cause a retraction also of the deadbolt 33. It is therefore quite apparent that when the deadbolt is projected and the door is open, the swinging shut of the door will not damage any of the parts because the latchbolt will effect the retraction of the deadbolt. However, with the deadbolt projected as in Fig. 3 into the opening 37 of the strike, a push or pull movement of the door will not be effective to retract the deadbolt because the deadbolt will impinge against the surfaces of the strike defining the opening 37, all as will be quite apparent.

A lock of the particular class is especially adapted for use on bathrooms. Thus, any one wishing privacy need merely rotate the inside knob 26 to lock the door. Thereafter, to leave the bathroom, the knob 26 is rotated to retract the deadbolt 33, whereupon a pull action will open the door.

In the event that the bathroom is locked from the inside and the occupant becomes ill, it is important to have an emergency release mechanism. This I provide in my lock. Thus, the deadbolt 33 is formed with a further rack portion 45 that is adapted for coaction with a pinion 46 rotatably mounted within the casing 14 as best illustrated in Fig. 4. Glancing at Fig. 4, it will be seen that the pinion 46 has a stub shaft 47 mounted in a bore 48 of the part 16 of the casing 14. At the other side of the pinion 46 there extends a stub shaft 49 rotatable in casing part 15 and grooved at 50 so that it may be actuated by a screw driver. An eyelet 51 is applied to the door 10 in alignment with the slot 50 of the stub shaft 49 so that any tool or other device fitting within the slot 50 may be used to rotate the pinion 46 and retract the deadbolt 33. It is quite apparent that through the means indicated, I am able to provide emergency release of the deadbolt when necessary. I believe that my invention will now be fully apparent to those skilled in the art.

I now claim:

1. In a lock of the class described, a casing, a latch bolt mounted for sliding movement in said casing, a spring pressing said latch bolt outwardly of said casing toward latching position, a strike with which said latch bolt co-acts yieldingly when spring projected from said casing, said strike and latch bolt being formed so that transverse swinging of said latch bolt relatively to said strike as when said lock is on a swinging door will cam said latch bolt into said casing against the force of said spring, a dead bolt slidably mounted in said casing and juxtaposed relatively to said latch bolt, said strike having an opening into which said dead bolt is movable when projected, a knob spindle rotatable in said casing, a knob on said spindle adapted to rotate said spindle, said spindle and knob being adapted

for securing against endwise movement relatively to said lock casing, and means rotatable with said spindle and engaging a part of said dead bolt for projecting and retracting said dead bolt relatively to said casing and into and out of locking relation to said strike, while a push or pull movement on said knob and spindle is adapted to swing said casing relatively to said strike to cam said latch bolt into or out of latching relation to said strike.

2. In a lock of the class described, a casing, a latch bolt mounted for sliding movement in said casing, a spring pressing said latch bolt outwardly of said casing toward latching position, said latch bolt coacting yieldingly with a portion of a strike when spring projected from said casing, said latch bolt being formed for coaction with the strike so that transverse swinging of said latch bolt relatively to said strike as when said lock is on a swinging door will cam said latch bolt out of latching position and into said casing against the force of said spring, a dead bolt slidably mounted in said casing and adapted to interlock with said strike when projected, a knob spindle rotatable in said casing, means rotatable with said knob spindle and engaging a part of said dead bolt for projecting and retracting said dead bolt relatively to said casing and into and out of locking relation to said strike, a push or pull movement on said knob spindle being adapted to swing said casing relatively to said strike to cam said latch bolt into or out of latching relation to said strike, a portion of said latchbolt extending beyond said deadbolt when both said latchbolt and deadbolt are fully projected relatively to said casing and said casing swings with a door from an open toward a closed position whereby said latchbolt impinges first against the strike, and means whereby the consequent retraction of said latchbolt by said strike retracts said deadbolt into said casing.

3. In a lock of the class described, a casing, a latchbolt mounted for sliding movement in said casing, a spring pressing said latchbolt outwardly of said casing toward latching position, said latchbolt coacting yieldingly with a portion of a strike when spring projected from said casing, said latchbolt being formed for coaction with the strike so that transverse swinging of said latchbolt relatively to said strike as when said lock is on a swinging door will cam said latchbolt out of latching position and into said casing against the force of said spring, a dead bolt slidably mounted in said casing and juxtaposed relatively to said latchbolt, said strike having an opening into which said deadbolt is movable when projected, a knob spindle rotatable in said casing, a pinion mounted in said casing and rotatable with said spindle, a rack formed as a part of said deadbolt and cooperable with said pinion for projecting and retracting said deadbolt relatively to said casing upon rotation of said knob and spindle, a push or pull movement of said knob and spindle being adapted to swing said latchbolt and casing relatively to said strike, a portion of said latchbolt extending beyond said deadbolt when both said latchbolt and deadbolt are fully projected relatively to said casing and said casing swings with a door from an open toward a closed position whereby said latchbolt impinges first against the strike, and means whereby the consequent retraction of said latchbolt by said strike retracts said deadbolt into said casing.

4. In a lock of the class described, a casing, a

latchbolt mounted for sliding movement in said casing, a spring pressing said latchbolt outwardly of said casing toward latching position, said latchbolt coacting yieldingly with a portion of a strike when spring projected from said casing, said latchbolt being formed for coaction with the strike so that transverse swinging of said latchbolt relatively to said strike as when said lock is on a swinging door will cam said latchbolt out of latching position and into said casing against the force of said spring, a deadbolt slidably mounted in said casing, said strike having a portion with which said deadbolt is cooperable when projected, a portion of said latchbolt extending beyond said deadbolt when both said latchbolt and deadbolt are fully projected relatively to said casing and said casing swings with a door from an open toward a closed position, whereby said latchbolt impinges first against the strike, and means whereby the consequent retraction of said latchbolt by said strike retracts said deadbolt into said casing.

5. In a lock of the class described, a casing, a latchbolt mounted for sliding movement in said casing, a spring pressing said latchbolt outwardly of said casing toward latching position, a strike with which said latchbolt coacts yieldingly when spring projected from said casing, said strike and latchbolt being formed so that transverse swinging of said latchbolt relatively to said strike as when said lock is on a swinging door will cam said latchbolt into said casing against the force of said spring, a deadbolt slidably mounted in said casing and juxtaposed relatively to said latchbolt, said strike having an opening into which said deadbolt is movable when projected, a knob spindle rotatable in said casing, a knob on said spindle adapted to rotate said spindle, said spindle and knob being adapted for securing against endwise movement relatively to said lock casing, a pinion mounted in said casing and rotatable with said spindle, a rack formed as a part of said deadbolt and cooperable with said pinion for projecting and retracting said deadbolt relatively to said casing upon rotation of said knob and spindle, a push or pull movement of said knob and spindle being adapted to swing said latchbolt and casing relatively to said strike, a second rack formed on said deadbolt, and a second pinion rotatable in said casing for retracting said deadbolt and adapted for access from that side of the lock opposite the side on which said knob is available.

6. In a lock of the class described, a casing, a latchbolt mounted for sliding movement in said casing, a spring pressing said latchbolt outwardly of said casing toward latching position, said latchbolt coacting yieldingly with a portion of a strike when spring projected from said casing, said latchbolt being formed for coaction with the strike so that transverse swinging of said latchbolt relatively to said strike as when said lock is on a swinging door will cam said latchbolt out of latching position and into said casing against the force of said spring, a deadbolt slidably mounted in said casing and adapted to interlock with said strike when projected, a knob spindle rotatable in said casing, means rotatable with said knob spindle and engaging a part of said deadbolt for projecting and retracting said deadbolt relatively to said casing and into and out of locking relation to said strike, a push or pull movement on said knob and spindle being adapted to swing said casing relatively to said strike to cam said latchbolt into or out of latching relation to said strike, a portion of said latchbolt being formed to contact

the strike in advance of said deadbolt when said latchbolt and deadbolt are fully projected from said casing and said casing swings with a door from an open toward a closed position, whereby said latchbolt impinges first against the strike, and means whereby the consequent retraction of said latchbolt by said strike retracts said deadbolt into said casing.

7. In a lock of the class described, a casing, a latchbolt mounted for sliding movement in said casing, a spring pressing said latchbolt outwardly of said casing toward latching position, said latchbolt coacting yieldingly with a portion of a strike when spring projected from said casing, said latchbolt being formed for coaction with the strike so that transverse swinging of said latchbolt relatively to said strike as when said lock is on a swinging door will cam said latchbolt out of latching position and into said casing against the force of said spring, a deadbolt slidably mounted in said casing and adapted to interlock with said strike when projected, a knob spindle rotatable in said casing, means rotatable with said knob spindle and engaging a part of said deadbolt for projecting and retracting said deadbolt relatively to said casing and into and out of locking relation to said strike, a push or pull movement on said knob and spindle being adapted to swing said casing relatively to said strike to cam said latchbolt into or out of latching relation to said strike, a portion of said latchbolt being formed to contact the strike in advance of said deadbolt when said latchbolt and deadbolt are fully projected from said casing and said casing swings with a door from an open toward a closed position, whereby said latchbolt impinges first against the strike, and a surface on said latchbolt impinging against a surface of said deadbolt for retracting said deadbolt into the casing as said latchbolt is retracted.

8. In a lock of the class described, a casing, a latchbolt mounted for sliding movement in said casing, a spring pressing said latchbolt outwardly of said casing toward latching position relatively to a strike, a deadbolt slidably mounted in said casing and adapted to interlock with said strike when projected, a portion of said latchbolt being formed to contact the strike in advance of said deadbolt when said latchbolt and deadbolt are fully projected from said casing and said casing swings with a door from an open toward a closed position, whereby said latchbolt impinges first against the strike, and means whereby the consequent retraction of said latchbolt by said strike retracts said deadbolt into said casing.

9. In a lock of the class described, a casing, a latchbolt mounted for sliding movement in said casing, a spring pressing said latchbolt outwardly of said casing toward latching position relatively to a strike, a deadbolt slidably mounted in said casing and adapted to interlock with said strike when projected, a portion of said latchbolt being formed to contact the strike in advance of said deadbolt when said latchbolt and deadbolt are fully projected from said casing and said casing swings with a door from an open toward a closed position, whereby said latchbolt impinges first against the strike, and a surface on said latchbolt impinging against a surface of said deadbolt for retracting said deadbolt into the casing as said latchbolt is retracted.

10. In a lock of the class described, a casing, a latchbolt movably mounted in said casing, a spring pressing said latchbolt relatively to said casing and toward latching position relatively to a strike, the contact of said latchbolt with said

strike moving said latchbolt into retracted position against the force of said spring, a deadbolt slidably mounted in said casing and adapted to interlock with said strike, a portion of said latchbolt so related to the strike whereby to contact the strike in advance of said deadbolt when said latch bolt and deadbolt are fully projected from said casing and said casing swings with a door from an open toward a closed position, whereby said latchbolt impinges first against the strike, and means whereby the consequent retraction of said latchbolt by said strike retracts said deadbolt into said casing.
